SPAT OR SIMILAR ARTICLE

Madeleine J. Bollenbach, Chicago, Ill.

Application November 21, 1952, Serial No. 22,402

Term of patent 14 years

(CL. D7—7)

To all whom it may concern:

Be it known that I, Madeleine J. Bollenbach, a citizen of the United States, residing at Chicago, in the county of Cook and State of Illinois, have invented a new, original, and ornamental Design for a Spat, or Similar Article, of which the following is a specification, reference being had to the accompanying drawings, forming a part thereof, in which

Fig. 2 is a side elevational view of the spat taken from the right of Fig. 1;

Fig. 3 is a rear elevation thereof; and

Fig. 4 is a side elevational view taken from the left of Fig. 1.

I claim:

The ornamental design for a spat or similar article, substantially as shown.

MADELEINE J. BOLLENBACH.
